UNITED STATES PATENT OFFICE.

CORNELIUS COLLINS, OF LOS ANGELES, CALIFORNIA.

FRAME CONSTRUCTION.

Application filed February 19, 1927. Serial No. 169,479.

This invention relates to a frame construction for fireproof walls, floors, suspended ceilings or the like, and has for its object to simplify and improve the manufacture, assembly and durability of the same. A more specific object of this invention is the provision of a novel form of attachment member whereby the channels or other supporting means to which the plaster receiving medium is secured are held in place on the studs or joists of the frame.

These objects together with other objects and corresponding accomplishments are obtained by means of the embodiment of my invention illustrated in the accompanying drawing in which:

Fig. 1 is a perspective view of a fragment of a wall illustrating the use of my attachment member; Fig. 2 is a vertical section 20 through the wall of Fig. 1, certain parts being broken away to illustrate the steps of assembling; Fig. 3 is a cross-section as seen on line 3—3 of Fig. 1; Fig. 4 is a perspective view of a fragment of a suspended ceiling illustrating the use of my attachment member on a different form of supporting element; Fig. 5 is a cross-section as seen on line 5—5 of Fig. 4; Fig. 6 is a bottom view 30 of the supporting element of Fig. 4, details of the ceiling construction being omitted from these two figures; and Figs. 7 and 8 are perspective views of my attachment means as applied to other forms of supporting members.

Referring with more particularity to Figs. 1, 2 and 3 of the drawing, a wall is shown constructed of studs or supporting elements 10 to which are attached transverse members or channels 11. Plaster lath 12 or any preferred form of plaster receiving medium is secured to the latter and a coating of cementitious plaster 14 in turn applied to this. A stud 10 as illustrated comprises four angles 15 secured by welding or riveting to 40 lattice bars 16 and has attachment members for channels 11 formed of bars 17 extending between the angles and beyond them on either side, being likewise held in place by welding or riveting. Each of these bars has a flange 18 disposed intermediate the angles for stiffening and is formed with right angle extensions located outside of the angles. Each extension comprises a saddle having a seat disposed between a pair of upstanding legs 20 and 21 adapted to embrace a channel 11, these being bent down over it to hold

the channel in place as the erection of the frame progresses. Each channel 11 has projecting prongs 22 adapted to be bent back toward the channel to hold the plaster lath 60 or wire lath in position thereon.

In Figs. 4, 5 and 6, a different form of supporting element is shown; in this case, as used for a joist. It comprises a web plate 25 to which are secured angles 26 by welding or riveting. Angles 27 for lateral stiffness may be similarly secured to the web plate. The web plate has projections 28 corresponding to the saddles 19 in the preceding embodiment. These projections 70 form attachment means for channels 29 which are arranged to have plaster lath secured to them. It will be noted that these projections are formed on only one side of the web, but it will be evident that they 75 could be formed on both sides and this element used as a stud as previously described; similarly the stud could be used as joist. The web performs both the function of the lattice bars 16 and the bars 17 of the element 80 first described.

In Fig. 7 I have shown one of my improved attachment members indicated by 35 secured to an ordinary hot rolled channel 36, of the type generally used in structural steel work. Member 35 may have extensions and upstanding legs as before described on both sides of the channel as shown, or only one side, and may be secured to the channel by welding or riveting either before or after 90 the channel is placed in the structure.

In Fig. 8 the extensions 37 carrying upstanding legs are similar to the saddles of the preceding forms, but in this case are shown integral with a channel 38, which 95 may be of the pressed type. A leg of the channel has an extension projecting from its edge which extension is bent back against the outer wall of the channel leg. This extension has a saddle formed therefrom.

What I claim is:

1. An attachment member of pliant metal for a supporting element, comprising a saddle outstanding from said supporting element having a seat extending transverse to the axis of said element, said saddle having legs arranged to straddle a transverse bar whereby said bar may be clamped to said seat.

2. An attachment member of pliant metal 110 for a metallic supporting element, comprising a saddle outstanding from said support-

ing element having a seat disposed at right angles to the axis of said element, said saddle having a pair of legs parallel to said axis arranged to straddle a transverse bar 5 whereby said bar may be clamped to said seat.

3. An attachment member for a metallic supporting element, comprising a portion projecting beyond said supporting element 10 having a seat disposed at right angles to the axis thereof, said seat having a leg adapted to embrace a transverse member extending at right angles to said axis and resting on said seat whereby said transverse member 15 may be secured to said attachment member.

4. An attachment member for a metallic supporting element, comprising a plate lying in the plane thereof and having a portion projecting beyond the edge of said supporting element including a seat disposed at right angles to the axis of said supporting element and adapted to support a transverse bar, said seat having legs adapted to straddle said bar and be bent over it, whereby to 25 secure said bar to said attachment member.

5. The combination of a metallic supporting element, an attachment member of pliant metal secured to said supporting element, and a transverse bar supported by said attachment member, said attachment member comprising a saddle outstanding from said supporting element having a seat disposed at right angles to the axis thereof, said saddle having a pair of legs parallel to said axis 30 arranged to straddle said transverse bar whereby said bar may be clamped to said seat.

6. The combination of a metallic supporting element, an attachment member secured to said supporting element, and a transverse 40

bar extending at right angles to the axis of said supporting element supported by said attachment member, said attachment member comprising a portion projecting beyond said supporting element having a seat disposed at right angles to the axis thereof, said seat having a leg adapted to clamp said transverse member to said seat whereby said transverse member may be secured to said supporting element. 45

7. The combination of a metallic supporting element, an attachment member secured thereto, and a transverse bar secured to said attachment member, said attachment member comprising a plate lying in the plane of 50 said supporting element including a seat disposed at right angles to the axis of said supporting element, said seat having a pair of legs embracing said transverse bar, whereby said bar is secured to said supporting element. 55

8. The combination of a plurality of supporting members, attachment members secured thereto and outstanding therefrom to provide seats, and transverse bracing and 60 lathing bars secured to said seats. 65

9. The combination of two pairs of angle members, the angle members of a pair being mounted flange to flange, attachment angle members interposed between the juxtaposed flanges and slotted to accommodate the angle members of a pair, said angle members being secured together to form a latticed supporting stud with outstanding seats for transverse bars. 70

In witness that I claim the foregoing I have hereunto subscribed my name this 8th day of February, 1927. 75

CORNELIUS COLLINS.
